UNITED STATES PATENT OFFICE.

SIMON JONES, OF NEW YORK, N. Y.

COLLAAPSIBLE CRIB.

1,113,647.

Specification of Letters Patent. Patented Oct. 13, 1914.

Application filed October 5, 1912. Serial No. 724,161.

To all whom it may concern:

Be it known that I, SIMON JONES, citizen of the United States, residing at New York city, in the county and State of New York, have invented certain new and useful Improvements in Collapsible Cribs, of which the following is a specification.

This invention relates to a new and useful improvement in cribs and is designed to furnish a crib which may be folded and at the same time be sanitary.

The device is especially intended for use in hospitals, schools or other places where there are a number of children in the same room or where the cribs are located together.

A crib such as is herein set forth may be folded so as to occupy a small space and a number of them may be kept ready at hand for use. At the same time the crib is so constructed that there are scarcely any loose or open places where unsanitary matter may find a lodgment and cling therein.

In the drawings: Figure 1 represents a perspective view of the crib ready for use. Fig. 2 is an enlarged plan view of one end of the crib. Fig. 3 is an end view of the device opened for use. Fig. 4 is a transverse section of the crib folded. Fig. 5 is a top view of a portion of the folded crib.

In these drawings, the numeral 1 designates a crib or similar structure which has the supporting legs 2, 2 and 3, 3 on casters 4, a pair of legs 2 and 3 on each side having rigidly secured to them the bottom and top longitudinal rails 5 and 6 to which are rigidly secured the vertical rods 7, each pair of legs, the rails secured thereto and the rods, forming a rigid side of the crib. Each post 2, 2 and 3, 3 has on the inside secured to it the two brackets 8 and 9, one bracket 8 near the top and the other bracket 9 about in a line with the bottom longitudinal bar 5. Each bracket has a horizontal arm 10, through which there is a hole, the holes of a pair of brackets on each leg 2 and 3 being in line vertically.

Passing loosely through the alined holes of each pair of brackets is a vertical rod 11. At each bracket the rod 11 passes through two ears 12, 12 which are on opposite sides of the horizontal arm 10, these ears 12, 12 being formed upon the top and bottom rails 13 and 14 of the ends 15 of the crib 1. The top and bottom rails 13 and 14 are connect-

ed by vertical rods 7 similar to the rods 7 of the sides. At their middles the ends 15 are hinged together by hinges 16 and 17 of the top and bottom rails, a vertical rod 18 forming the hinge bolt for both hinges. At the bottom hinge 17 of the bottom rail 14 there is secured at the inside of the hinge to one section of the rail 14 a finger 19 which extends out over and beyond the bottom hinge 17. When the crib is opened for use, these fingers bear against the hinges and stiffen the bottom rails.

One of the rigid sides of the crib is provided on the inside with a longitudinal rod 20 which is secured at its ends 21, to the bottom rail 5 near its ends.

The bottom 22 of the crib is made of longitudinal slats 23, which are secured at their ends 24 to end slats 25. These end slats 25 are made with loops 26 which pass around the rod 20. The slat 23 at the edge of the bottom away from the loop side of the end slats 25 has two catches 27 adapted to hook over the bottom rail 5 of the side of the crib. The bottom 22 is made of a size 80 and shape to fit snugly within the sides and ends of the crib. And the loops 26 are of such length that the bottom may be raised up and down on the rod 20 and be held either vertically alongside of the side of the 85 crib or be turned down within the sides and ends, the catches 27 holding it firmly in place.

The posts 2, 2 and 3, 3 have orifices 28 in the tops in which are caught the ends of 90 two canopy holders 29, 29 which not only serve to support a canopy but also aid in holding the crib rigid when extended.

The end slats 25 being made with the loops 26, the latter are thus part of the 95 structure of the bottom 22, integral with the bottom and not merely fastened to it. Hence in use these loops would not be pulled loose from the bottom. The fingers 19 give to the joints formed by the bottom hinges 100 17 a rigidity which has the effect of stiffening the bottom rails 14 so that when extended they are like solid rails.

By the use of the canopy holder 29, 29, these form spreaders bracing the hinged 105 ends and aiding in preventing any accidental movement of the hinged parts. They also act to keep the hinged parts of the ends extended and aid the fingers 19 in giving rigidity to the ends when open and thus to 110

the entire crib. They also aid in preventing the occupant of the crib from moving the hinges with liability of injury.

As has been stated, this crib is designed primarily for use when there are a number of children. Manifestly it has great advantages. But a folding crib should have only as many loose places as is possible for its operation. The present device is intended to reduce these to a minimum. Hence all the joints which are necessary in the construction of the crib, except those used for the operation of folding, are riveted. Not only does this riveting prevent loosening of parts but it makes the crib sanitary as nothing unsanitary can be lodged in the jointed places, the riveting effectually preventing this.

The operation of the device is obvious from its construction. The bottom is swung up and slid down vertically alongside of the sides, the canopy holders are removed, the ends are folded together at their hinges and the sides come together forming a flat device which may be readily handled and

packed away. For use, the operation is reversed and the crib is ready.

Having described my invention, what I claim is:

As a new article of manufacture, a collapsible crib, composed of two rigid sides, two ends hinged to the sides and hinged at their middles by top and bottom hinges, fingers at the bottom hinges on the inside adapted to stiffen the hinged ends, the ends having orifices in their tops, spreaders held in such orifices and adapted to brace the hinged ends and aid in preventing any accidental movement of the hinged parts, a longitudinal rod secured at its ends to one of the rigid sides and a slideable bottom having end slats made with loops which pass around the rod.

In testimony whereof I affix my signature in presence of two witnesses.

SIMON JONES.
